UNITED STATES PATENT OFFICE.

THOMAS EDGAR AUD, OF HERNDON, VIRGINIA.

LIFE-SAVING DEVICE.

1,065,017.

Specification of Letters Patent. Patented June 17, 1913.

Application filed September 23, 1912. Serial No. 721,905.

To all whom it may concern:

Be it known that I, THOMAS EDGAR AUD, a citizen of the United States, residing at Herndon, in the county of Fairfax and 5 State of Virginia, have invented certain new and useful Improvements in Life-Saving Devices; and I do declare the following to be a full, clear, and exact description of the invention, such as will enable 10 others skilled in the art to which it appertains to make and use the same.

This invention relates to improved life saving devices, and more particularly to water-proof union garments for this purpose.

The object of the invention is to provide a simply constructed life preserver in the form of a garment for incasing the entire body except the face, and constructed to 20 protect the wearer against both wet and cold.

Another object of the invention is to provide a garment of this class which may be quickly applied and which will reliably 25 support the wearer with his head and shoulders above water.

With this and other objects in view, the invention consists of certain novel features of construction, combination and arrangement of parts, as will be more fully described and claimed.

In the accompanying drawings, Figure 1 represents a front elevation of the garment in position on the wearer before the closures 35 are secured; Fig. 2 is a similar view with all of the closures in place except the collar and the hood; Fig. 3 is a front elevation of this improved garment in operative position on the wearer's head for use; Fig. 4 is a rear elevation thereof; Fig. 5 is a horizontal section taken on the line 5—5 of Fig. 3; Fig. 6 is a detail longitudinal sectional view through the entrance tube and a portion of the body and one leg of the 45 garment with the tube in open position; Fig. 7 is a detail sectional view of the tube partially closed; Fig. 8 is a detail longitudinal vertical section through one of the feet of the garment.

50 In the embodiment illustrated, a one-

piece body incasing garment 1 is shown in the form of what is commonly known as a union suit having feet and hand pockets contiguous therewith and with an entrance tube to facilitate the donning of the garment. This garment 1 is constructed of any suitable water-proof material and is provided with a lining 2 of wool or other suitable non-conducting heat retaining material to protect the wearer against cold when the body is immersed in icy water. This garment is provided at its upper end with an opening 3 which is preferably V-shaped as shown at 4 to adapt the head of the wearer to pass easily therethrough. 55 Secured within this opening 3 is a guimpe or shield 5, preferably constructed of elastic material such, for instance, as thin rubber which will readily stretch and may be folded into a small space when desired. 60 The lower edge of this shield is secured to the edge of the opening 3 by cementing or in any suitable manner to render its connection therewith water-proof. This shield 5 has a tubular neck encircling portion 6 which is sufficiently large to permit the head of the wearer to be inserted therethrough when the garment is applied as 65 shown in Fig. 1. This neck portion is gathered around the neck of the wearer by 70 a strap 7 and is made sufficiently long to be turned down over the strap as shown in Fig. 2 in a manner similar to the collar of a turtle-neck sweater and which not only forms additional warmth around the neck 75 of the wearer but serves to prevent any passage of water. A rubber collar 8 is preferably clasped over the folded down neck portion and is secured in position by means of a suitable clasp 8' adapted to be adjustably connected with one of a series of openings 8''.

A protecting storm collar 9 is arranged over the elastic neck portion and the auxiliary collar 8 and over the shield 5. This collar 9 extends down over the back of the garment and is permanently secured thereto below the opening 3 therein and is provided with side flaps 10 and 11 which form the front portion thereof, and are adapted to 100

be adjustably closed by means of clasps 12 or other adjustable fastening elements which will permit the collar to fit persons of different sizes, the edges of said collar being overlapped to prevent the entrance of water. The sides and lower edges of this collar are preferably secured in position by means of clasps 13.

One or more annular casings or pockets 14 extend around the body portion of the garment 1, one being here shown and composed of any suitable strong fabric. These pockets or casings 14 have a suitable buoyant material 15 inserted therein which will support the occupant with his head and shoulders above water. While one only of these pockets has been shown it is, of course, to be understood that any desired number may be employed.

20 Inflatable water wings 16 and 17 are formed on the shoulders of the garment and when the lower portion of the body of the wearer is submerged in water the air contained in the garment will be forced upward 25 into these water wings and inflate them as shown in Figs. 3 and 4, thereby providing floats to assist in sustaining the weight of the wearer.

To provide for the quick application of this garment, it is provided with an entrance tube 18 communicating with an opening in the body of the garment at the front thereof at a point below the float pocket 14 and above the bifurcation or leg portion. This 35 opening and tube are sufficiently large to permit the body of the wearer to pass therethrough and the legs to be inserted in the legs of the garment. The body portion of the garment is then drawn upward and the 40 head passed through the neck portion and the arms placed in the sleeves. The mouth of this tube 18 has a casing 19 extending half-way therearound in which is inserted a belt 20 as shown in Figs. 1 and 6. After the 45 wearer enters the garment through the tube 18 and passes his head through the neck portion thereof as shown in Fig. 1, the mouth of the tube is closed by folding it inwardly over the belt as shown in Fig. 7, until it is entirely 50 rolled up adjacent the waist of the wearer. The belt 20 is then passed around the back of the wearer and brought to the front and secured by a buckle 21 or other suitable fastening. The collars are then adjusted and the fastenings thereof secured.

A hood 22 is preferably used to protect the head of the wearer and as shown, is constructed with a flaring depending skirt 23 to fit around the neck and shoulders of the 60 wearer and to readily shed water therefrom and prevent its entrance thereunder.

Fastening clips or clamps 24 are preferably provided at the ankles of the garment to hold it in position on the foot of the

wearer which is especially necessary when 65 weights 25 are employed as shown in Fig. 8. These weights 25 are designed to hold the feet of the wearer under the water to prevent them from floating or coming to the surface, and are preferably removable.

70 While I have described my invention with more or less minuteness as regards details and as being embodied in certain precise forms, I do not desire to be limited thereto unduly any more than is pointed out in the 75 claims. On the contrary, I contemplate all proper changes in form, construction and arrangement, the omission of immaterial elements and substitution of equivalents as 80 circumstances may suggest or render expedient.

I claim as my invention:

1. A life preserving device comprising a water-proof union garment having at its top an adjustable opening for the passage of the 85 head, an entrance tube of the same width as the waist portion of the body of the garment and having its open inner end secured transversely across the waist, the communication of the tube with the garment being independent of the opening at the top of the garment, said tube being of sufficient length to permit its open outer end to be flattened and rolled upon itself up to the waist to render it water-tight, and means for securing 90 the rolled portion of the tube around the 95 waist.

2. A life preserving device comprising a water-proof union garment having a neck portion for insertion of the head therethrough and provided with suitable closures, a flexible and substantially cylindrical entrance tube extending from and communicating with the waist portion of the body of the garment, said tube having its open inner end secured transversely across the waist, the communication of the tube with the garment being independent of the opening at the top of the garment, said tube being of sufficient length to permit its open outer end to be flattened transversely and rolled inwardly upon itself up to the waist line to render it water-tight, a casing extending half-way around the outer end of the tube, a strap passed through the casing to provide 105 a stiffening element on which the tube may be rolled, the ends of the strap being extended, and means for adjustably fastening the strap to secure the rolled portion of the tube around the waist of the wearer.

3. A life preserving device comprising a water-proof union garment having water wings secured to the upper portion of the garment and communicating with the interior thereof whereby air may be forced 115 into said wings from the body of the garment when pressure is exerted from below.

4. A water-proof union garment having

an opening at its upper end provided with an adjustable closure, a yieldable collar encircling said closure and a protecting storm collar arranged over said yieldable collar, and a buoyant element carried by said garment.

In testimony whereof I have hereunto set

my hand in presence of two subscribing witnesses.

THOMAS EDGAR AUD.
